UNITED STATES PATENT OFFICE.

NICHOLAS ERNEST REESOR, OF MARKHAM, COUNTY OF YORK, ONTARIO,
CANADA.

GATE-OPENING DEVICE.

SPECIFICATION forming part of Letters Patent No. 337,618, dated March 9, 1886.

Application filed August 6, 1885. Serial No. 173,743. (No model.) Patented in Canada August 8, 1885, No. 22,230.

To all whom it may concern:

Be it known that I, NICHOLAS ERNEST REESOR, of the township of Markham, in the county of York, in the Province of Ontario, Canada, have invented an Improved Gate-Opening Device, of which the following is a specification.

The object of the invention is to provide an improved device of that class by which a gate may be opened by the vehicle about to be driven through it and closed by the same vehicle without the driver descending from his seat; and it consists in the peculiar combinations and the novel construction and arrangement of parts, all as more fully hereinafter described and claimed.

Figure 1 is a perspective view showing my improved gate-opening device applied to an ordinary farm-gate. Fig. 2 is a detail showing the form of the support on which the gate is hinged and through which the vertical spindle passes. Fig. 3 is a detail of the holdfast for the latch.

A is the gate, provided with hinges B, securely bolted to it and designed to fit over the hollow supports C, which are securely fastened to the gate-post D, as indicated.

E is a vertical hinge-rod or spindle passing through hollow supports C, and having a crank, a, formed on its top end, as indicated. This crank is attached to the block or weight F by the cord or chain, b. This cord or chain passes over a swivel-pulley, d, which is arranged and located as indicated, so that it will turn upon its pivot to accommodate the position of the crank a on whichever side of the gate A it may at the time be pulling. The block or weight F is carried on suitable guide-rods, G, which are secured to the gate A, as indicated, and the weight is intended to be so connected to them that it will slide freely vertically when drawn upon by the cord or chain b.

H is a quadrant or segment of a pulley attached to the end of the spindle or hinge-rod E. I are two double-cranked trip-rod, located one on each side of the gate A, and carried horizontally in suitable bearings, as indicated, the cranks being set at right angles to each other and arranged so that when one is horizontal and out of the way, the other crank on the same trip-rod is vertical and projects

above the ground. On the end of each double-cranked trip-rod I fix a pulley, J, and connect the said pulleys on opposite sides of the gate by the rod and chain K, so that when one pulley is caused to revolve a corresponding motion is imparted to the other pulley.

L also represents rods or chains to connect the pulleys J to the quadrant H, as indicated in Fig. 1, so that when either of the double-ended trip-rod I is caused to rock upon its bearing a corresponding motion is imparted to the quadrant H, and as this quadrant is connected to the spindle or hinge-rod E a corresponding movement is imparted to the said spindle.

M is a double arm fixed to the spindle or hinge-rod E, and connected, as indicated, to the spring-latch N by the rods or chains O.

P is a notched hasp, into which the spring-latch N fits.

Having now described the general construction of the parts involved in my invention, a few words will suffice to explain its operation. I will assume that the vehicle is being driven toward the left-hand side of the gate A. The wheel will then strike the crank f on the double-cranked trip-rod I, causing the trip-rod to rock on its bearing and draw upon the rod K, which is connected, as before described, to the two pulleys J. Consequently the pulley on the opposite or right-hand side of the gate is caused to revolve, and will therefore draw upon its rod L, which is connected to the quadrant H, fastened to the spindle or hinge-rod E, thereby causing the said spindle or hinge-rod to revolve in the direction indicated by the arrow. As the spindle or hinge-rod moves in this direction, the weight F will be raised, and at the same time the spring-latch N drawn back out of the notch in the hasp P, when the gate will naturally swing back in the direction indicated by the arrow to the holding-post Q, where a corresponding hasp, P, is located, as indicated. By connecting the spindle E to the gate through a movable weight, F, the movement of the gate is produced in a quiet and gradual manner, avoiding the shock to the various parts, which would occur if the double-cranked trip-rod I were connected directly to a fixed portion of the gate. By forming the hasp P as shown in Fig. 3—that is to

say, placing a piece of spring-rubber, *g*, behind it—the shock of the gate in closing is entirely overcome.

What I claim as my invention is—

5 1. The combination of the gate *A*, hinged upon hollow supports, the hinge-rod *E*, passing through said supports, the movable block or weight *F*, connected with said rod, the quadrant *H*, secured to said rod, and the double-
10 cranked trip-rod *I*, connected with said quadrant, substantially as and for the purpose specified.

2. The combination of the gate *A*, hinged upon the hollow supports *C*, the vertical hinge-
15 rod *E*, having a crank-arm, *a*, at its top, which passes through said supports and is connected to the movable block or weight *F*, as described,

and the double-cranked trip-rod *I*, connected to the hinge-rod *E*, substantially as and for the purpose specified.

20

3. The post *D*, hollow supports *C*, attached thereto, vertical hinge-rod *E*, and the gate *A*, hinged upon said hollow supports, and the double arm *M*, formed on said hinge-rod, in combination with the spring-latch *N*, connected to said arm and arranged to engage with the hasp *P*, substantially as and for the purpose specified.
